US00D691893S

(12) **United States Design Patent**
Finlay et al.

(10) **Patent No.:** **US D691,893 S**
(45) **Date of Patent:** **** Oct. 22, 2013**

(54) **BOTTLE**

(75) Inventors: **Patrick J. Finlay**, New Fairfield, CT (US); **Jennifer Antczak**, Darien, CT (US); **Jacinthe Brillet**, Rueil Malmaison (FR); **Michael Goldenberg**, Brooklyn, NY (US); **Brent Lindberg**, Saint Charles, IL (US)

(Continued)

(73) Assignee: **PepsiCo, Inc.**, Purchase, NY (US)

FOREIGN PATENT DOCUMENTS

(**) Term: **14 Years**

CA 106315 3/2006
GB 4000790 12/2006
GB 4005313 11/2007

(21) Appl. No.: **29/407,183***Primary Examiner* — Sandra Morris(22) Filed: **Nov. 23, 2011***Attorney, Agent, or Firm* — Banner & Witcoff, Ltd.(51) **LOC (9) Cl.** ..... **09-01****CLAIM**(52) **U.S. Cl.**

The ornamental design for a bottle, as shown and described.

(58) **Field of Classification Search****DESCRIPTION**

USPC D9/600, 655–664, 516, 547, 559–561,
D9/569–575; 206/457, 527; 215/400;
220/890

See application file for complete search history.
